The ornamental design for a toy vehicle track portion, as shown and described.

DESCRIPTION

FIG. 1 is a top perspective view of a toy vehicle track portion according to an embodiment of the present invention;

FIG. 2 is a bottom perspective view of the toy vehicle track portion of FIG. 1;

FIG. 3 is a top view of the toy vehicle track portion of FIG. 1; FIG. 4 is a bottom view of the toy vehicle track portion of FIG. 1;

FIG. 5 is a right side view of the toy vehicle track portion of FIG. 1;

FIG. 6 is a left side view of the toy vehicle track portion of FIG. 1;

FIG. 7 is a front view of toy vehicle track portion of FIG. 1; FIG. 8 is a rear view of the toy vehicle track portion of FIG. 1; and,

FIG. 9 is a top view of a first toy vehicle track portion of FIG. 1 engaging a second toy vehicle track portion in accordance with FIG. 1.

The broken lines shown in the figures are included for the purpose of illustrating the unclaimed portions of the article and form no part of the claimed design.
